UNITED STATES PATENT OFFICE.

NEWITT J. NEALL, OF BROOKLINE, AND RALPH W. CHADBOURN, OF MELROSE, MASSACHUSETTS, ASSIGNORS TO OXFORD PAPER COMPANY, OF NEW YORK, N. Y., A CORPORATION OF NEW YORK.

ELECTRODE FOR ELECTRIC BOILERS.

Application filed November 5, 1924. Serial No. 747,971.

In an application for United States Letters Patent filed November 5, 1924, Serial No. 747,970, we have described and claimed an improved method of operating electric steam boilers and a novel boiler, and have set forth in detail the fundamental considerations which we have discovered in relation to the operation of these boilers. In the course of these experiments, we have discovered that 5 the form of the live electrode or electrodes employed has an important bearing on the efficiency of the boiler.

The present invention therefore has to do with new and improved electrodes for electric 15 boilers, the object of the invention being to provide electrodes which to the largest possible extent will tend to reduce arcing and the disassociation of gases with the objectionable accompanying effects which are described in our companion application. Dis- 20 association of gases occurs when the current passes through dry vapor as, for instance, through steam bubbles.

In the course of the experiments referred 25 to, we discovered that where a cylindrical or pipe-shaped electrode is employed, as has commonly been the case in electric steam boilers, there is formed on the outside of the electrode an envelope of steam, and under 30 some conditions of disassociated gases, and that in the area of active steam formation there is produced a colloid-like substance which lowers the resistivity of the solution with the result that arcing is likely to take 35 place. We have also found that arcing is most likely to take place when the steam envelope is large and thick and the area of active steam production is closely adjacent the surface of a cylindrical electrode. The particu- 40 lar object therefore of the present invention is to provide an electrode which will produce an area of steam formation such that the smallest possible envelope about the electrode surface is formed and therefore the 45 conditions will be least favorable for arcing and consequent disassociation of gases.

As pointed out in our said companion application, we have solved the problem of the diminishing resistivity of the solution in the 50 boiler by introducing feed water which has a maximum resistivity at the region of active steam formation, that is, closely adjacent the surface of the central electrode, and we remove the concentrate as it is formed, prefer-

ably by means of pipes around the outside of 55 the boiler on the level with the region of maximum steam formation.

The invention will be fully understood by reference to the following description when taken in connection with the accompanying 60 drawing, and the novel features thereof will be pointed out and fully set forth in the claims at the close of this specification.

In the drawings:

Fig. 1 is an elevation of an electrode and 65 means for introducing feed water to the region of active steam formation, the whole embodying our invention in its preferred form.

Fig. 2 is a vertical section of the electrode 70 shown in Fig. 1.

Fig. 3 is a plan view of the electrode shown in Fig. 1.

Fig. 4 shows another form of electrode embodying our invention. 75

Figs. 5, 6 and 7 are sections showing electrodes embodying our invention in modified form.

Referring now to the drawings, the electrode shown in Fig. 1 comprises a central 80 member 11 which is hollow to permit the introduction of water, and a hollow spiral member 13 forming the electrode proper, the spiral member being supported by cross arms 14 and 15 or in any other convenient way from 85 the central member 11. The electrode proper 13 is formed into what may be termed a conical helix or bedspring shape, this being the preferred embodiment of our invention. The electrode proper is hollow and is perforated 90 at intervals, as shown at 131 and at its upper end is connected to the center member so that feed water may be introduced through the electrode proper as well as through the central member to the localities of active steam 95 formation.

The electrode proper 13 is connected electrically with the wire carrying the incoming current, the shell of the boiler (not shown) being grounded in the usual way. 100

As shown in the drawings, the electrodes are placed in the boilers with the apex of the conical helix down. The electric current passes between the coiled pipe forming the electrode proper 13 and the other electrode or electrodes (not shown), the areas of current incidence being along the surface of the coiled electrode. The area of active steam 105

formation therefore follows the surface of the coiled electrode, and as the bubbles of steam form they immediately rise directly upward without being impeded or retarded by any part of the electrode or by interference with each other, and there is a minimum tendency to coalesce.

The upward direction of the movement of the bubbles is indicated, as at 16, by dotted lines. It will be seen that no unit of active surface of the electrode is vertically above any other unit of surface of the electrode and therefore the steam formed by any given unit of surface is free to rise to the surface of the water in the boiler without interfering with any other bubbles of steam. It is also seen that the paths of the bubbles of steam are not so located as to cause the bubbles to tend to coalesce with each other. There is therefore no area in which there is formed any considerable mass of steam through which it is necessary for the electric current to pass and therefore the possibility of arcing and consequent disassociation of gases is reduced to a minimum.

The feed water as explained is introduced in part through the central supporting member 11 and in part through the pipe forming the electrode proper and therefore enters the solution in the boiler at the area of active steam formation, thereby furnishing a solution of maximum resistivity for the electric current to act upon.

It will be seen that the bedspring shape of electrode shown in Fig. 1 gives the nearest possible approach to ideal conditions and therefore embodies our invention in its preferred form. Other forms of electrodes however embody our invention in somewhat less effective form, but still are a great improvement over the forms of electrodes heretofore employed.

In Fig. 4 we have shown an electrode of the bedspring shape having a central member 20 through which all the incoming water is introduced, the electrode proper 21 being of conical helix form and being solid and not serving for the introduction of water. Notwithstanding the fact that water is introduced entirely through the supporting member 20, it arrives at the region of active steam formation, and excellent results are produced.

In Fig. 5 we have shown an electrode composed of a hollow header 30 connected electrically by the pipe 31 both to the water supply and to the incoming current. To this header are secured a series of pipes, 32, 32, forming the electrodes proper. These pipes are hollow and inclined toward each other, closely approaching each other at the bottom. The entering water passes through the pipe 31, the header 30, down the pipes 32 and emerges from the orifices 33. Thence, such of it as

is not evaporated rises as it is heated along the surface of the electrodes 32, thus reaching easily the region of maximum steam formation. The steam bubbles produced rise to the surface and do not interfere with each other, although in actual practice they are likely to be of larger size than those formed by the bedspring type of electrode.

In Fig. 6, we have shown another electrode like that shown in Fig. 5, except that the depending electrode members 34 are solid and water is introduced through holes 35 in the header 30.

In Fig. 7, we have shown still another electrode having a header 40 and electrodes proper 41. These are hollow and have vertical portions with the lower ends inturned to form a sort of cylindrical basket. Since the chief region of steam formation is near the tips of the electrodes and further since the areas of the individual electrodes are relatively small, there is much less interference and a less objectionable envelope of steam is formed than is the case with cylindrical electrodes of the kind heretofore ordinarily employed. Furthermore, we believe the shape of electrode with tips further from the boiler than the other portions of the electrode provides more efficient conditions on account of more uniform current distribution.

What we claim is:

1. The improved electrode for electric steam boilers comprising a hollow member having an effective portion at an angle to the vertical to be submerged in the solution so that steam bubbles formed by the effective portion will tend to rise individually vertically to the surface, said hollow member being connected to permit the introduction of fresh water through the hollow member.

2. The improved electrode for electric steam boilers comprising an electrically effective member of conical helical shape, said member being hollow to permit the introduction of feed water therethrough.

3. The improved electrode for electric steam boilers comprising a hollow member which has an electrically effective portion at an angle to the vertical and an orifice or orifices adjacent the electrically effective portion, and means for supplying water through the electrode and the said orifice or orifices.

4. The improved electrode for electric steam boilers comprising a hollow central member for the introduction of water and a pipe connecting at one end with the said central member and bent into conical helical form said pipe being provided with orifices for the emission of feed water.

In testimony whereof we affix our signatures.

NEWITT J. NEALL.
RALPH W. CHADBOURN.
